UNITED STATES PATENT OFFICE

WILLIAM H. NEELY, OF DETROIT, MICHIGAN, ASSIGNOR TO GRAHAM-PAIGE MOTORS CORPORATION, A CORPORATION OF MICHIGAN

DESIGN FOR AN INSTRUMENT BOARD PANEL

Application filed March 17, 1933. Serial No. 47,489. Term of patent 14 years.

To all whom it may concern:

Be it known that I, WILLIAM H. NEELY, a citizen of the United States, residing at Detroit, in the county of Wayne and State of Michigan, have invented a new, original, and ornamental Design for an Instrument Board Panel, of which the following is a specification, reference being had to the accompanying drawing, forming a part thereof, in which—

Figure 1 is a front elevational view of the instrument board panel showing my new design.

Fig. 2 is a sectional view of the same taken on the line 2—2 of Fig. 1, looking in the direction indicated.

I claim:

The ornamental design for an instrument board panel, as shown.

WILLIAM H. NEELY.
